CLAIM

The ornamental design for a safety net, as shown and described.

DESCRIPTION

FIG. 1 represents an overhead view of the safety net, showing my new design;

FIG. 2 represents a close-up view showing a portion thereof;

FIG. 3 represents a close-up view showing another portion thereof;

FIG. 4 represents a close-up view of a portion of a single chord thereof; and,

FIG. 5 represents a close-up view of a portion thereof.

The design is shown broken away along its length and width in FIG. 1 to indicate that no specific length is claimed.

1 Claim, 4 Drawing Sheets

FIG. 1

FIG. 4

FIG. 5
